UNITED STATES PATENT OFFICE

2,477,857

ANNUNCIATOR

John Boeve and John Sterenberg, Holland, Mich.

Application August 4, 1944, Serial No. 548,094

2 Claims. (Cl. 161--3)

1

This invention appertains to new and useful improvements in annunciators, the principal object being to provide a horn or alarm circuit for producing an audible signal for the purpose of orientating huntsmen or persons lost especially in forests.

Another important object of the invention is to provide an orienting annunciator especially intended for the purpose stated and which can be easily installed on automobiles and elsewhere, where electricity is available.

Other objects and advantages of the invention will become apparent to the reader of the following description.

In the drawings:

Figure 1 represents a front elevational view of the annunciator.

Figure 2 is an inside rear elevational view, the rear cover being removed.

Figure 3 is a vertical sectional view through the device.

Figure 4 is a sectional view through the rotor.

Figure 5 is a fragmentary top plan view of the rotor.

Figure 6 is a diagrammatic view showing the electrical connection between the electrical elements involved.

Referring to the drawings wherein like numerals designate like parts, it can be seen that numeral 5 generally refers to a box-like structure having a top 6, a bottom 7, side walls 8 and a front frame 9 in which a window 10 is mounted. This box has a rear closure 11 hinged in place as at 12 and provided with a fastener 13.

Inside of the box, which can be mounted suitably on an automobile or other vehicle, is a clock 14, especially of the alarm clock type. The clock is of conventional design and includes a shaft 15 performing one revolution per hour which is used in conjunction with the present invention.

In carrying out the present invention a circumferentially grooved disk 16 of insulation is secured to the shaft 15 and radially through this disk and having its linear or strip like ends exposed in the circumferential groove thereof are conductor sections 17 arranged along a diameter of the disk which the spring contact fingers 18, 19 can engage. A post 20 anchors the contact finger 18, while the contact finger 19 is carried by a post 21.

Jumpers 22, 23 extend from the posts 20, 21 to a switch 24 mounted on the upper portion of the box 5 and operative from the outside of the box.

Numerical 25 denotes an electric horn, grounded at one side and having a conductor 26 extending from the other side thereof to the post 20. A

2

source of current 27 has one side grounded and its other side connected by a jumper 28 to the diametrical conductor sections 17 in the rotor 16.

It can now be seen, that when the switch 24 (see Figure 6) is open and the apparatus is operating, when one end of the diametrical conductors 17 engages the contact finger 18, current will be supplied from the battery 27 to the conductor 26 and horn 25, thus energizing the horn for a few moments and this will be repeated every half hour, so long as the switch 24 is open. However, in the event it is desired to offer more frequent signals, the switch 24 is closed, thus bringing into use, the spring contact finger 19, so that alternately with the use of the finger 18, the finger 19 comes into play, engaging the ends of the conductor sections 17 with the result that current passes from the battery 27 to the parts 17 and from there to the finger 19, jumper 23, switch 24, jumper 22, to the conductor 26.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A device for producing a periodic audible signal of limited duration comprising an electric horn, a clock mechanism provided with a time controlled minute shaft, a rotor disk of insulating material on said shaft, provided with a radial bore, a contact piece in said bore with a substantially linear conducting end surface, exposed on the periphery of the disk, a conductor leading to the conducting contact piece in said radial bore, a source of current connected with said conductor, a plurality of contact fingers, sliding on the periphery of the aforesaid rotor disk for cooperation with the contact piece in the radial bore, said contact fingers being set for contact with the periphery of the rotor disk at an angular distance less than 180°, a connection between one of said contact fingers with the electric horn, and a connection between said horn and source of current completing the circuit, whereby signals of limited duration are produced, and a manually disconnectable connection between the said finger and a further finger, having its point of contact on the rotor disk set at an angular distance from the first named finger, for changing the frequency of the audible horn signal.
2. A device for producing periodic audible signals of limited duration, comprising an electric

horn, a clock mechanism provided with a time controlled minute shaft, a rotor disk of insulating material on said shaft, provided with a radial bore, a contact piece in said bore with substantially linear conducting surfaces, exposed on the periphery of the disk at diametrically opposed points, a conductor leading to the conducting contact piece in the radial bore, a source of current connected with said conductor, a contact finger sliding on the periphery of the aforesaid rotor disk and cooperating with the substantially linear contact piece ends, a connection between said contact finger and said horn, at least one further contact finger, sliding on the periphery of the said disk, said contact finger being in contact with the periphery of said rotor disk at an angular distance from the contact point of the first named finger with said disk, said distance not exceeding an angle of 90°, an electric connection between said contact fingers, and a manually operated switch in said connection, an electric

10

20

connection including the first mentioned contact finger, horn and source of current, whereby signals of limited duration twice for every full rotation of the shaft at predetermined intervals are produced and the closure of the switch in the connection between the fingers increases the frequency of the signals emitted by the horn.

JOHN BOEVE.
JOHN STERENBERG.
